EDWARD EDMUND MULLINS, OF HABANA, CUBA.

STANDPIPE.

Application filed November 15, 1920. Serial No. 424,238.

To all whom it may concern:

Be it known that I, EDWARD EDMUND MULLINS, a citizen of the United States, and resident of Habana, Cuba, have invented a new and Improved Standpipe, of which the following is a full, clear, and exact description.

My invention relates to stand pipes, and aims to provide a device of this nature, more particularly intended for use in connection with rail-way engines.

It is a well appreciated fact that stand pipes heretofore were used for supplying fluid to a locomotive, such fluid being either in the nature of water or fuel oil, and that numerous accidents have occurred in that the attendant has not returned the parts to such a position that they do not extend over the right of way.

In this instance, subsequent trains have struck the stand pipe resulting in damage to both the same and the trains. Also it has been necessary for the operator to get on top of the tank or tender of the locomotive and to manipulate various rods etc., to swing the outer end of the pipe to the position desired, and to actuate the valves.

Further, stand pipes heretofore placed upon the market have been capable of but a limited movement, so that extreme difficulty has been experienced in placing the discharge end centrally over the intake opening, unless a hose or other flexible connection is utilized.

It is also well understood that a great waste of liquid has occurred, which in case fuel oil is being utilized, has involved considerable expense, for the reason that a certain amount of liquid has escaped, subsequent to the shutting off of the valves by the operator removing the discharge end from the receiving opening before all of the fluid has finished trickling from the discharge end.

Having these defects in mind, I have now constructed a stand pipe in which primarily the operator will be compelled to return the parts to a position at which they lie in a position out of the path of the passing vehicle, as well as including structure which will lock the parts of the stand pipe in its returned or retracted position.

A further object of my invention is the construction of a device of this nature which

may be operated from the ground or a platform, so that it is not necessary for the operator to climb upon the top of the tank, also permitting the operator to dispense with the tackle incident to the operation of a device of this nature, as now utilized.

A still further object of my invention is the provision of a stand pipe which may be practically universal in its movement, so that the discharge end of the same may be moved to any desired position.

Another object of my invention is the provision of a construction which will prevent the waste of the liquid and avoid the necessity of having to drain the swinging or open arm, which in the case of heavy viscous liquids, involves the expenditure of a considerable amount of time.

Further objects of my invention will appear in the annexed specification and drawings, which latter present one practical embodiment of my invention, and in which—

Figure 1 is a side view of the parts in their normal or locked position.

Figure 2 is a similar fragmentary view, but showing the parts in the position which they will assume during the discharge of the liquid.

Figure 3 is a fragmentary plan view of the device as illustrated in Figures 1 and 2, and

Figure 4 is an enlarged sectional view taken on the line 4—4 of Figure 1.

In these views the reference numeral 5 indicates any suitable type of supply pipe, projecting from the ground, and preferably positioned adjacent the track 6.

A secondary pipe 7 forming an extension of the pipe 5 and connected thereto by means of an interposed valve 8, is provided, which pipe mounts the discharge arm.

The arm or pipe conveniently includes a downturned outer end portion 9, connected by any suitable means to the pipe 10, which latter in turn is connected to the pipe 7.

Referring specifically to this connection, and with a view of providing a coupling which will permit of universal movement on the part of the discharge pipe, reference is had to Figure 4, in which it will be seen that the reference numeral 11, indicates a suitable gland, which bears against a packing 12, confined within the stuffing box 13, which latter may conveniently co-operate with a

2
collar 14, enveloped by the base 15 of a hollow T member, all of these parts inter-engaging by any suitable means, such as conventional screw threads, and encircling the 5 upper end of the pipe 7.

A tapered metal plug 16 formed with an opening 17, is positioned within the arms of the hollow T, the opening 17 of the same being in line with the opening of the base 10 of the T-shaped member, and being, as has been indicated, of a width slightly larger than the same.

The plug 16 may be conveniently seated within the arms of the T-shaped member 18, by any suitable means such as a nut 15 and washer 19 and 20, respectively.

It will now be appreciated that that portion of the plug 16 which projects beyond the outer end of the arm of the T 18 is 20 firmly secured to a suitable connecting member 21, or directly to the pipe 10.

It will also be noted that the pipe 10 is provided with a portion 22 extending beyond the point of connection with the pipe 7, and it will be appreciated that this extending portion may be conveniently weighted, so as to counter-balance the pipe to permit of its rear movement.

It will also be noted that by means of the 30 connection provided, that the pipe 10 is capable of rotating about the pipe 7 through a complete circle, and that the pipe 10 may also be rocked with respect to the pipe 7, to an angle of approximately 45° thus permitting 35 the universal movement desired.

Now with a view of providing means which will serve to permit of a rear movement of the pipe 10, and at the same time insure the return of this member to a position 40 at which no danger of contact of the same with trains may be felt, it will be seen that I conveniently utilize a ring 23, which is adapted to encircle the pipe 7, and to bear against a suitable guiding element 24.

45 The ring 23 pivotally mounts, as at 25, one end of a rod 26. A further rod 27 extends between the rod 26, and the extended portion 22 of the pipe 10, and has its ends pivotally secured one to each of these members respectively. In this connection it will be noted that a rotation of the pipe 10 may be effected by swinging the rod 26, which movement will be imparted through the rod 50 27 to the pipe 10.

55 Also an oscillating of this latter pipe may be effected by the swinging movement on the part of the rod 26, in a vertical plane by virtue of the same connecting medium specified. Thus an operator may stand upon the 60 ground or a platform, and swing the outer end of the pipe 10 to any point desired.

To provide suitable locking means, a hasp 28 is conveniently affixed to the rod 26, and it will be noted that this hasp is capable of 65 encircling the spindle 29 of the valve 8, in

which position it may be secured, by any suitable type of lock 30, to prevent its further movement.

The hand wheel 31 of the valve is conveniently provided with a series of cut out 70 portions 32, and it will be noted that the rod 26 seats in these cut out portions when the hasp is in the position shown in Figure 1, thus also locking the valve.

Also the rod 26 may be conveniently provided with an extended portion 33 pivotally secured to the outer end of the main portion of the rod 26, these parts being retained in line with one another, when this is desired, by any suitable means, such as a pin 80 34 extending through openings formed in both of these members.

By extending the rod 26 greater leverage is afforded to this member, while a movement of the parts to the position illustrated 85 in Figure 1 serves to provide compactness.

From the foregoing it will be appreciated that I have provided a stand pipe, the discharge end of which may primarily be moved universally to overcome the defects set 90 forth in the preamble. Also this movement may be effected by an operator upon the ground, and without the use of any cumbersome tackle, as has heretofore been customary.

It will further be understood that to lock the device, it will be necessary for the operator to bring the parts to their normal position, at which they entirely clear the track 6, and in this position it will be noted that the discharge pipe 10 has its outer end inclined upwardly so that any undrained liquid within the same will flow back into the pipe 7 and thus not trickle onto the ground, as is now the case, and by means of 105 which it becomes a total loss.

Obviously numerous modifications of structure might readily be resorted to without in the least departing from the spirit of my invention, which I claim as—

1. In a stand pipe, a main pipe, a discharge pipe, means for mounting the discharge pipe on the main pipe, whereby it may swing through a complete circle and through an arc transverse to the plane of the circle, a pivoted operating lever mounted to turn on the main pipe, and a rod having one end pivoted to said lever and its other end pivotally connected with the discharge pipe.

2. In a stand pipe, a main pipe, a member mounted to turn on the upper end of the main pipe, a discharge pipe pivotally mounted intermediate of its ends on said member, a member mounted to turn on the main pipe intermediate of its ends, an operating lever pivoted to the last named member, and a rod pivoted to the lever and pivotally connected with the discharge pipe at one side of its pivot.

3. In a stand pipe, a main pipe, a **T** member mounted to turn on the upper end of the pipe, a discharge pipe having intermediate of its ends a hollow and apertured plug 5 mounted to turn in the said member, a ring mounted to turn on the main pipe, an operating lever pivoted to the ring, and a rod having one end pivoted to the lever and its other end pivoted to one end of the discharge pipe.

4. In a stand pipe, a main pipe, a discharge pipe mounted on the upper end of the main pipe to swing in a circle and in an arc transverse to the plane of the circle, a 15 valve in the main pipe, a pivoted operating lever mounted to turn on the main pipe, a rod pivoted to the lever and to the discharge pipe, and means for locking the said lever and valve.

5. In a stand pipe, a main pipe, a discharge pipe mounted on the upper end of

the pipe to swing in a circle and in an arc transverse to the plane of the circle, a pivoted operating lever mounted to turn on the main pipe, a rod pivoted to the operating 25 lever and discharge pipe, a valve in the main pipe, and a hasp on said lever and adapted to engage the valve stem and to be locked thereto.

6. In a stand pipe, a main pipe, a discharge pipe mounted on the upper end of the main pipe to swing horizontally in a circle, and in an arc transverse to the plane of the circle, a pivoted operating lever mounted to turn on the main pipe, a rod 30 connecting the lever with the discharge pipe, a valve in the main pipe and having its operating wheel provided with notches with which the lever is adapted to engage, and a hasp on the lever and adapted to engage the valve stem and to be locked thereto.

EDWARD EDMUND MULLINS.
